UNITED STATES PATENT OFFICE.

STUART BAGGS BLAIR, OF MARQUEZ, TEXAS.

AUTOMOBILE SEAL-HOLDER.

1,274,668.

Specification of Letters Patent. Patented Aug. 6, 1918.

Application filed April 17, 1918. Serial No. 229,110.

To all whom it may concern:

Be it known that I, STUART B. BLAIR, a citizen of the United States, and a resident of Marquez, in the county of Leon and State 5 of Texas, have invented certain new and useful Improvements in Automobile Seal-Holders, of which the following is a specification.

My invention relates to improvements in 10 adjustable holders, adapted more particularly for holding the registry seals carried by automobiles, and it consists in the construction and arrangement herein described and claimed.

15 An object of my invention is to provide an adjustable spring clamp or holder arranged in such a manner that when it is clamped onto a part of the automobile, as for instance the radiator tube, a clamping 20 action is also had on the registry seal, thus holding both in place.

Other objects and advantages will appear in the following specification, reference being had to the accompanying drawing in 25 which:

Figure 1 is a front elevation of a registry seal showing how the invention is employed to support the seal,

Fig. 2 is a plan view of the holder,

30 Fig. 3 is a front elevation of the holder,

Fig. 4 is a cross section on the line 4—4 of Fig. 3, and

Fig. 5 is a cross section on the line 5—5 of Fig. 2.

35 In carrying out my invention I provide a metallic bar 1 which is bent at right angles at the extremities at 2; each of the right angularly bent portions 2 terminates in a fixed jaw 3 which co-operates with a movable 40 jaw 4 to clamp upon some suitably disposed portion of the automobile as for instance a pair of the radiator tubes 5.

45 Ears 6 formed on the portions 2 adjacent to the base of each of the jaws 3, receive 50 pintles 7 on which the spring clamps 8 of which the movable jaws 4 are a part, are pivoted. Each spring clamp 8 has a loop 9 into which a finger may be inserted to pull the clip 10 away from a pin 11 on a sliding sleeve 12 so that the registry seal 13 may be inserted.

55 The sliding sleeve 12 is mounted on the bar 1 and held in place by bending the rear ends over as shown in Fig. 4. A slot 14 in the clip 10 of the spring clamp 8 receives the pin 11 and the length of the slot 14 limits

the adjustment of the sliding sleeve 12 along the bar 1. It is necessary to adjust the sliding sleeve 12 to accommodate various sizes of the seals 13. The seal 13 has suitably 60 punched holes which are set over the pins 11 upon pulling the clips 10 out in the manner just explained.

A double function is performed by the 65 spring clamp 8 on each side. The nature of the spring clamp is such that when the holder is free from the tubes 5, the movable jaw 4 will be pressed against the adjacent stationary jaw 3. This leaves the clip end 10 entirely disengaged from the pin 11 so that 70 there is a passage between the end of the pin and the adjacent surface of the clip 10. Now on fitting the jaws 3 and 4 over a tube 5 the spring clamp 8 is rocked on the pivot 7 so that the spring clip 10 moves down 75 closely upon the sliding sleeve 12. The remaining action can now be readily understood since when it is desired to insert a seal 13 into position, the clip 10 is simply lifted so that the seal may be slipped in 80 place over the pin 11 on each side.

The resilient nature of the clamp 8 causes 85 it to tightly bind on the seal to hold it in place. The primary purpose of the loop 9 in each clamp 8 is to make the clips 10 resilient, but the loop 9 may equally as well be employed to raise the clips by inserting the finger as previously described. The free ends of the jaws 3 and 4 are rounded outwardly as shown in Fig. 2 to facilitate the 90 introduction of the tubes 5 between the jaws. The tension of the clip 10 may be increased by simply pressing down upon the loop 9 whereupon the clip 10 will bear more tightly 95 on the registry seal and against the adjacent sliding sleeve 12.

Located in the middle of the bar 1 is an arm 15 which has spring jaws 16 on the free end for engaging another of the radiator tubes 5. This arm 15 provides a central 100 brace for the bar 1 and prevents any undue vibration of the bar which might otherwise occur. There is one outstanding feature of importance in this invention which should be emphasized. There are no screws or nuts 105 that hold the various parts together, to work loose by vibration of the automobile to which the device is attached. By reason of the omission of screws and nuts, the seal holder does not constantly require attention as is 110 always the case where such devices are employed to fasten the parts together.

While the construction and arrangement of the holder as described and illustrated, is that of a generally preferred form, obviously modifications and changes may be made without departing from the spirit of the invention or the scope of the claims.

I claim:—

1. A registry seal holder including a bar, means carried by the bar for supporting a seal, and means carried by the bar for simultaneously clamping the bar to a support and the seal to said supporting means on the bar.
2. A registry seal holder including a bar having the ends formed into stationary jaws, means adjustably mounted on the bar for receiving a registry seal, a spring clamp pivoted adjacent to each stationary jaw and having a movable jaw coöperating with the stationary jaw, a clip included in each spring clamp coöperating with said adjustable seal holding means to exert a tension on said seal to hold it in place, said clip binding upon the seal when the coöperating jaws are thrust upon a support, and means including a loop formed in the spring clamp for increasing the tension of said clip.
3. In a seal holder, a bar, means including a sliding sleeve adjustably mounted on the bar, means including a pin carried by the sleeve for receiving a seal, and means mounted on the bar including a clip having a slot arranged to fit over the pin and engage the seal to hold it in place, the range of adjustment of the sliding sleeve being limited by the length of said slot.
4. In a seal holder, a bar having a right

angled portion terminating in a fixed jaw, means carried by the bar for supporting a seal, and a resilient clamp pivoted on the bar with a movable jaw normally pressing on the fixed jaw with a clip in normal disengagement with said seal holding means, said clip being urged under tension to bind on the seal and seal holding means on forcing the movable jaw from the stationary jaw in introducing said jaws to a support.

5. In a registry seal holder, a bar having the extremities bent at right angles thereto and terminating in fixed jaws having rounded ends, ears formed at the bases of the jaws, seal holding means carried by the bar including sliding sleeves with portions bent over the bar, a pin carried by each of the sleeves, and a spring clamp pivoted between each of the pair of ears, each clamp including a coöperating jaw having a rounded portion, a clip having a slot arranged to fit over the pin on the sliding sleeve, and a loop formed in the clamp providing a finger hold and means for increasing the tension of said clips.

6. In a registry seal holder, a bar, fixed jaws formed on the ends of the bar, movable members forming coöperating jaws, said jaws being adapted to fit over the adjacent tubes of a radiator, means on the bar coacting with portions of the movable jaws for receiving and holding a registry seal, and an arm having a jaw on the end, fixed on the bar and providing a central support.

STUART BAGGS BLAIR.
